(57) **CLAIM**

The ornamental design for a car, including toy car, motor car, replica car and scale model car, as shown and described.

DESCRIPTION

FIG. 1 is a front left side perspective view of the car, including toy car, motor car, replica car and scale model car showing our new design;

FIG. 2 is a rear left side perspective view thereof;

FIG. 3 is a top view thereof;

FIG. 4 is a left side view thereof;

FIG. 5 is a front view thereof;

FIG. 6 is a rear view thereof;

FIG. 7 is a right side view thereof; and,

FIG. 8 is a bottom view thereof.

Any broken lines in the figures illustrate portions of the car, including toy car, motor car, replica car and scale model car that form no part of the claimed design.

1 Claim, 8 Drawing Sheets
